United States Patent Office

Des. 228,563
Patented Oct. 9, 1973

228,563

GOLF CLUB HEAD

George C. Brower, 2308 Pacific Ave.,
Long Beach, Calif. 90806

Filed July 28, 1972, Ser. No. 276,092

Term of patent 14 years

Int. Cl. D21—02
U.S. Cl. D34—5 GH

FIG. 4

FIG. 1 is a perspective view of the golf club head showing my new design;

FIG. 2 is an elevational view showing the rear face of the golf club head;

FIG. 3 is a top plan view of the golf club head;

FIG. 4 is a bottom plan view of the golf club head;

FIG. 5 is an elevational view showing the front face of the golf club head;

FIG. 6 is an end elevational view of the golf club head taken from the rear of the club.

I claim:

The ornamental design for a golf club head, as shown.
